UNITED STATES PATENT OFFICE.

WILLIAM H. TULLY, OF MONROE, MAINE.

WRENCH.

Application filed June 11, 1925. Serial No. 36,454.

My invention relates to improvements in wrenches in which a movable jaw is slideable along a handle or shank carrying a stationary jaw and in which co-acting teeth 5 are provided on the shank and movable jaw for holding the latter in adjusted position, spring means being provided for laterally shifting said movable jaw to interengage the aforesaid teeth. While wrenches of this 10 general type have heretofore been devised, it is the aim of my invention to greatly simplify and cheapen their construction, at the same time providing a more desirable and efficient tool.

15 With the foregoing in view, the invention resides in the novel subject matter herein-after described and claimed, the description being supplemented by the accompanying drawing.

20 Figure 1 is a side elevation of a wrench constructed in accordance with my invention.

Fig. 2 is a longitudinal sectional view, the shank and stationary jaw being shown in 25 elevation.

Fig. 3 is a transverse sectional view as indicated by line 3—3 of Fig. 2.

In the drawings above briefly described, the numeral 1 designates a straight elongated shank which may be of any desired 30 proportions, the front end of said shank being provided with a stationary jaw 2 which projects laterally from one edge thereof, this edge being formed with a plurality of 35 teeth 3 at points spaced in rear of the aforesaid jaw.

Slidable freely upon the shank 1, is a substantially flat sleeve 4 having at its front end an integral laterally projecting jaw 40 5. The sleeve and jaw are preferably molded in a single piece, as shown, and the edge wall 6 of said sleeve, adjacent the toothed edge of the shank 1, is formed with an integral tooth 7 to engage any of the 45 teeth 3. This edge wall is also formed with a transverse opening 8 which is parallel to the plane of the aforesaid toothed edge of the shank 1. The opposite edge wall 9 of the sleeve 4 is formed with a relatively large 50 opening 10 leading from the exterior to the interior of said wall and having its axis disposed at right angles to the axis of the opening 8.

55 A one-piece U-shaped yoke 11 straddles the sleeve 4 and has its parallel arms 12 disposed at the side walls 13 of said sleeve,

while the arm-connecting portion 14 of said yoke is outwardly spaced from the edge wall 9 and the opening 10 thereof. This arm connecting portion 14 is provided with a 60 stud 15 which extends into the opening 10, and a coiled compression spring 16 surrounds said stud and passes through said opening, the outer end of the spring being in contact with the portion 14 of the yoke, 65 while the inner end of said spring contacts with the smooth edge of the shank 1. A rivet 17 passes through the arms 12 and through the opening 8 of the edge wall 6, said rivet securing the yoke 11 to the sleeve 70 4, so that the action of the spring 16 exerted against the yoke, will cant said sleeve to some extent, insuring successive engagement of the tooth 7 with the teeth 3 when the sleeve is forced forwardly. The spring 75 also functions to engage the teeth of the shank and sleeve after the sleeve 4 has been moved by hand to disengage said teeth and rearwardly adjust the sleeve.

A wrench constructed in accordance with 80 my invention is of extreme simplicity and possesses an unusually small number of parts. By molding the movable jaw and its sleeve 4 and forming the openings 8 and 10 at the time of carrying out the molding 85 operation, a saving in cost of manufacture is produced and moreover, by forming one of these openings in one edge wall of the sleeve and the other opening in the opposite edge wall, neither of these walls is appreciably 90 weakened. The provision of the U-shaped yoke 11 to abut the outer end of the spring 16, permits this advantageous location of the opening 8 with respect to the opening 10, and as the arms of this yoke extend across 95 substantially the entire width of the side walls 13 and are unsecured by rivets or the like to these walls, the latter are in no manner weakened. Another advantage for the U-shaped yoke is that it affords effective 100 means to prevent slipping of the user's hand to adjust it and the movable jaw 5.

It will be seen from the foregoing that an exceptionally simple and inexpensive 105 wrench has been provided, yet that it will be efficient and very desirable, and as excellent results have been obtained from the details disclosed, such details are preferably followed. However, within the scope of the 110 invention as claimed, minor changes may be made.

I claim:

A wrench comprising an elongated shank having a plurality of spaced teeth on one edge and provided at its front end with a stationary jaw projecting from said edge, a flat elongated, one piece, sleeve slidable on said shank, said sleeve having a lateral jaw at its front end and an internal tooth at the rear end of one of its edge walls, said tooth being engageable with the shank teeth, the other edge wall of said sleeve having an opening near its rear end, a U-shaped metal yoke whose arms straddle said sleeve and are disposed at the side walls thereof and

whose arm-connecting portion is outwardly spaced from the aforesaid opening, a coiled compression spring passing through said opening and abutting said arm-connecting portion and said shank, a stud projecting into said spring from said arm-connecting portion, and a rivet passing through the free ends of said arms and through said sleeve, said rivet extending through the first named edge wall. 15

In testimony whereof I have hereunto affixed my signature. 20

WILLIAM H. TULLY. 25
